JAMES G. PRAGER, OF WORCESTER, MASSACHUSETTS, ASSIGNOR TO PRAGER CO., INC.,
A CORPORATION OF NEW YORK

DESIGN FOR WALL PAPER OR SIMILAR MATERIAL

Application filed March 17, 1930. Serial No. 34,938. Term of patent 3½ years.

To all whom it may concern:

Be it known that I, JAMES G. PRAGER, a citizen of the United States, and resident of Worcester, in the county of Worcester and State of Massachusetts, have invented a new, original, and ornamental Design for Wallpaper or Similar Material, of which the following is a specification.

In the accompanying drawing:—

The figure is a surface view of a piece of wallpaper or similar material showing the design. The area within the dot and dash lines represents one complete unit of the design, and the area outside of the lines rep-

resents repeat units arranged around the complete unit. The units are arranged in horizontal rows, and adjacent rows are offset one half a complete unit from each other so that the angle designated by letter A in the complete unit corresponds with angle B of a bottom repeat.

I claim:—

The ornamental design for wallpaper or similar material as shown and described.

Signed at New York in the county of New York and State of New York this 14th day of March A. D. 1930.

JAMES G. PRAGER.
